W. B. FOSTER,
GRAVITY CATCH FOR SLIDING SIDE CRIBS,
APPLICATION FILED DEC. 8, 1913.

UNITED STATES PATENT OFFICE.

WILLIAM B. FOSTER, OF UTICA, NEW YORK, ASSIGNOR TO FOSTER BROTHERS MANUFACTURING COMPANY, OF UTICA, NEW YORK, A CORPORATION.

GRAVITY-CATCH FOR SLIDING-SIDE CRIBS.

1,151,774.

Specification of Letters Patent. Patented Aug. 31, 1915.

Application filed December 8, 1913. Serial No. 805,195.

To all whom it may concern:

Be it known that I, WILLIAM B. FOSTER, of Utica, in the county of Oneida and State of New York, have invented certain new and useful Improvements in Gravity-
5 Catches for Sliding-Side Cribs; and I do hereby declare that the following is a full, clear, and exact description thereof, which will enable others skilled in the art to which 10 it appertains to make and use the same, reference being had to the accompanying drawings, and to the reference-numerals marked thereon, which form part of this specification.

15 My present invention relates to processes of making and assembling gravity catches and combinations of gravity catches and guide rod brackets for sliding side cribs and the like.

20 In most ordinary forms of cribs equipped with sliding sides the bracket which supports the gravity catch and also supports the guide rod upon which the sliding side operates must be secured to the corner post before the final finishing or enameling of 25 the post and bracket in order to prevent the affixing of the bracket marring the finish of the post or bracket. For the same reason the gravity catch pivotally mounted upon 30 the bracket has to be mounted upon the bracket before the bracket and post and preferably the catch are finished or the catch must be affixed with very great care to prevent the injuring of the finish or special 35 and more elaborate means must be employed to fasten the catch to the bracket after the parts have received their final finish. This assembling of the post, bracket and catch in all simple constructions before 40 the final finish is a disadvantage in that it necessitates all of said parts being finished in the same style or color and tends to clog up the bearing surfaces of the pivotal or swivel connection between the gravity catch 45 and the bracket.

The purpose of my present invention is to provide a process to obviate the above mentioned disadvantages by providing a construction wherein the parts may receive 50 their finish or enamel before the gravity catch is mounted upon the bracket and then the gravity catch be mounted and permanently secured in place without injuring the finish upon the catch, the bracket or the 55 post.

A further object of my invention is to provide an improved process of making a construction of the character described which is simple in manufacture, easy to assemble and strong and durable in use. 60

Figure 1 shows in side elevation the parts of one end of a sliding side crib illustrating my invention. Fig. 2 is a perpendicular sectional view on line 2—2 of Fig. 1. Fig. 3 is a horizontal sectional view of the parts 65 seen immediately below line 3—3 of Fig. 1. Fig. 4 is a plan or side view of the gravity catch as originally formed and shown as being passed over the broadened head of the bracket. 70

Referring to the drawing for a more particular description of the steps of my process the corner post 8 of the crib has secured thereto the necessary number of brackets 9 to support in upright position the usual 75 guide rods 10 upon which is slidably mounted the sliding side 11 as by the cross pieces 12 of the said side projecting therefrom and being provided with eyes 13 through which the guide rod 10 extends. 80

The projecting part of bracket 9 adjacent to the post 8 is preferably circular in cross section so as to form a neck 14 while the portion of said bracket therebeyond is made into a head 15 broader than said neck and 85 preferably flattened so as to be more conveniently perforated by a circular hole 16. Preferably the broadened head 15 will be so arranged as to lie in a substantially horizontal line with its two sides projecting beyond the line of the neck 14 so as to form 90 abrupt shoulders 17 facing toward the neck. The bracket 9 is secured in any suitable way to the post 8 at any convenient stage in the assembling of said parts and conveniently 95 before the finishing or enameling.

The gravity catch 18 having the usual hook 19 and the usual downward facing cam surface 20 is formed with an eye 21 circular in the main but provided with two 100 oppositely disposed outwardly extending recesses 22 as plainly indicated in Fig. 4. The diameter of the eye in its long way or from recess to recess is greater than the width of head 15 of bracket 9 and the width of the 105 recesses 22 is greater than the thickness of head 15 so that by placing the catch 18 in the position relative to head 15 indicated in Fig. 4 the eye of said catch readily allows 110 the catch to be passed over the head 15 and,

through the circular part of said eye being larger than the neck 14, back upon said neck. It will then be obvious that by releasing said catch it will swing downwardly and 5 hang in swiveling relation upon said neck 14 and would be retained thereon as long as the catch was not moved to horizontal position since the shoulders 17 would in any depending position of the catch engage that 10 part of the catch adjacent to the circular portion of the eye 21 and would not mesh with the recesses 22. However to prevent such an accidental displacement and to render the catch at all times operative the catch 15 is permanently mounted upon the bracket 9 in the following manner: The eye portion of the catch is so shaped and formed and the catch composed of such material that the eye may be slightly compressed in a line at 20 right angles to its greatest diameter by relatively slight pressure which may be easily applied after the catch is in place on the bracket and without straining said catch and without damaging its finish. This compression of the catch about the eye 21 will 25 change the shape thereof from that shown in full lines to the shape indicated in dotted lines in Fig. 4 so that the two semicircular portions of the eye 21 will be brought nearer together forming almost a complete circle 30 loosely swinging upon the round neck 14 while the sides of each recess 22 have been brought toward each other enough so that the width of the said recesses is less than the 35 thickness of the shoulders 17 and head 15. It will then be obvious that even when the catch is moved to horizontal position relative to the head 15 the narrower recesses 22 will not pass the shoulders 17. It will be 40 noticed that through relying upon this compression only to prevent accidental disengagement only a relatively slight compression is necessary and the normal working or wear of the parts is taken care of by the 45 ample projection of shoulders 17. The cross piece 12 of the sliding side is extended beyond eye 13 so that as the sliding side is raised it will engage cam surface 20 upon the gravity catch and force said gravity 50 catch to one side until the end of said cross piece is engaged by hook 19 in the usual way as indicated in Fig. 2. Upon raising the sliding side slightly it may be disengaged from the gravity catches in an obvious 55 manner.

The means here shown for securing the gravity catch upon the crib is very strong and not at all likely to be so broken or strained as to let the catch escape. If, however, through any hard usage or accident the catch should be disconnected or the eye of the catch broken and so allow the catch

to come off, another catch may be mounted upon the bracket as already indicated without sending the crib to the factory and without any special tools or particular skill as all that is necessary is to slip the eye of the catch over the head of the bracket and compress the sides of the eye as already indicated. 65

Through the catch not being placed upon the bracket until the bracket and post have received their final finish and also not until the catch has received its final finish, it will be obvious that the catch may be of an entirely different material and especially may be supplied with entirely different finish or enamel. For the same reason it will be apparent that the contact portions of the swivel joint will not become clogged in the 70 75 80 finishing operations since the parts are separate and much more accessible.

What I claim as new and desire to secure by Letters Patent is:

1. The process of making a gravity catch 85 for sliding side cribs which consists of providing projecting from the crib post a bracket having a neck portion adjacent the post and an enlarged head therebeyond, and providing a gravity latch member having 90 an aperture in its upper end larger than said bracket head, placing said aperture over the bracket head and upon the neck portion thereof and then compressing the apertured end of the latch until its aperture is small 95 enough to prevent the latch being removed from the bracket but is still swingingly mounted on the neck portion thereof.

2. The process of making a gravity catch 100 for sliding side cribs which consists of providing projecting from the crib post a bracket having a neck portion adjacent the post and a head having laterally extending and horizontally arranged projections and providing a gravity latch member having an 105 aperture in its upper end larger than the body of the head and of the neck and having recesses extending outwardly from said main aperture and longitudinally of the latch, placing said latch upon the neck by 110 arranging the latch horizontally and passing the main aperture over the head and the recesses over the head projections and then compressing the apertured end of the latch until the latch cannot be removed 115 from the bracket even when horizontally arranged.

In witness whereof I have affixed my signature, in the presence of two witnesses, this 15th day of Nov., 1913.

WILLIAM B. FOSTER.
